UNITED STATES PATENT OFFICE.

JOHN BAUDINO, OF HERRIN, ILLINOIS.

COMBINED CAP AND ANTISPLASH DEVICE FOR GASOLINE TANKS.

Application filed April 12, 1922. Serial No. 551,899.

To all whom it may concern:

Be it known that I, JOHN BAUDINO, a citizen of the United States, and a resident of Herrin, in the county of Williamson and the State of Illinois, have invented certain new and useful Inventions in Combined Caps and Antisplash Devices for Gasoline Tanks, of which the following is a specification.

This invention relates to a cap of peculiar construction to be employed in connection with certain devices usually known as "gas savers" and applied to automobile engines for the purpose of saving the fumes generated in the tank, said fumes being mixed with air and drawn into the cylinders of the engine by suction. The practical use of these devices has been limited as when the tank is carrying a full supply of fuel and the automobile is driven over rough roads or places the gasoline is splashed into the pipe and carried into the cylinder causing fouling and faulty combustion. They have therefore operated only with partial success and then only as the supply of gasoline was largely depleted.

I have found that by applying my cap to one of these devices now in use this objection to it is entirely removed and that it operates perfectly at all time and even with a full supply of gasoline in the tank and on ordinary country roads, acting equally as well under these conditions as when used on perfectly smooth roads with only a small supply of gasoline in the tank.

My invention consists of the novel features of construction and combination of parts hereinafter described, pointed out in the claims, and shown in the accompanying drawings, in which:—

Figure 1 is a vertical section showing my invention complete and in position for use.

Figure 2 is a section on the line 2—2 of Fig. 1 looking upwardly.

Figure 3 is a section on the same line looking downwardly.

Figure 4 is a section on the line 4—4 of Fig. 1.

Figure 5 is a section on the line 5—5 of Figure 1.

In the drawings A designates a portion of a tank and B the filling vent flange. The usual filler cap is removed and my devices inserted in place of it.

This consists of a cylindrical body 1 having a lower internally threaded flange 2 to

engage the flange B. An annular chamber 3 is formed within the upper portion of the body 1 and communicates with a pipe 4 which leads to or forms part of the "gas saver." In the top of the body portion is an annular groove 5, and bores 6 connect the chamber 3 with said groove. The body 1 is provided with a dome shaped cap 7 which has an annular groove 8 coinciding with the groove 5 when the cap is threaded to the body 1, as shown in Figure 1. Bores 9 connect the groove 8 with the interior chamber 10 formed in the cap. A conical diaphragm 11 having vent openings 12 is carried by the cap, and in inverted position.

A packing ring 13 is placed between the cap and the body 1 and has openings 14 therein, through which communication is established between the grooves 5 and 8. The cap has also a vent 15 to the outer air.

Arranged within the body above described and supported by an interior shoulder is an inner cylinder 16, having a hand bar 18 to permit easy removal from the body 1. 80

Supported in the cylinder is an inverted cone diaphragm 19 covered by a horizontal diaphragm 20, the diaphragm 19 having suitable vents and the diaphragm 20 having slots 20^a offset with respect to the vents of 85 the diaphragm 19.

The packing ring 13 is of sufficient width to cover the top rim of the cylinder 16. A packing disc 21 is held to the bottom of the cylinder 16 by a retaining plate 22, 90 continuous bores 23 being produced through the plate, the disc and the cylinder bottom, the packing disc resting on the annular shoulder 17 of the body 1.

It will be noted that the vents in both the inverted cones are in their tip or central portions while the slots 20^a of the horizontal diaphragm are to one side of the center and out of alignment with those of the cones. 95

The operation of the device is as follows:

Suction from the engine through pipe 4 will draw in air through the vent 15 and will also draw vapor fumes from the tank 105 through the cones 19 and 11 and through the openings 20^a into the chamber 10 where they will mix with the incoming air. This mixture will then be drawn downwardly through bores 9, grooves 5 and 8, through 110 the ring openings 14, and by way of bores 6 to the annular chamber 3, becoming more

thoroughly mixed as they descend, and thence to the feed pipe 4. Any gasoline that may splash upwardly through the ports or bores 23 will strike the inverted cone 19 and any small amount that might wash through said cone vents will be stopped by the horizontal diaphragm 20, and if on very rough roads any small amount should pass through the openings 20 creeping of it up 10 the walls of the inner cylinder will be checked by the cone 11. Tests with the device show that it is practically impossible for any raw or unvaporized gasoline to reach the chamber 10 under any ordinary road or 15 operating conditions.

What I claim is:—

1. The combination with a filler cap having an air vent, of a series of perforated diaphragms carried by said cap and arranged in different horizontal planes, and means for conducting fumes passing through said diaphragms to a fuel supply pipe.

2. The combination with a tank having a filler opening, a filler cap carried thereby, 25 said cap comprising a cover portion removable from the body portion of the cap, an inner cylindrical portion removable from the body portion, said body portion having

air and gas mixing recesses formed therein, 30 perforated diaphragms carried by the cover portion and the inner cylinder, and a fuel supply portion in communication with the recessed portion of the body, said recessed portion also having communication through 35 said diaphragms with the tank and through said cover portion with the outer atmosphere.

3. The combination with a gasoline tank having a filler opening, a cylindrical body portion secured thereto and in communication with the interior of the tank through 40 said opening, a removable inner cylinder carried by the said body portion, perforated diaphragms carried by said inner cylinder, the perforations of one diaphragm being 45 offset with respect to the other, a cap for said body portion having an air vent, a perforated diaphragm carried by the cap, the body portion having an annular chamber formed therein said chamber having free 50 communication with the interior of the cap and with the outer air, and a fuel feed pipe in communication with said chamber.

In testimony whereof I affix my signature.

JOHN BAUDINO.
